ROTARY APPARATUS FOR PUMPING
VOLATILE LIQUIDSOdd A. Hansen, Kenmore, N. Y., assignor to The
Linde Air Products Company, New York, N. Y.,
a corporation of Ohio

Application July 13, 1940, Serial No. 345,309

4 Claims. (Cl. 62—1)

This invention relates to rotary apparatus for conveying or pumping a volatile liquid, and particularly to such apparatus adapted for pumping a liquefied gas having a boiling point materially below 273° K. at atmospheric pressure, for example, liquid oxygen.

The invention has for its object generally the provision of an improved arrangement and combination of elements for mounting the rotary element in pumps of the character indicated.

More specifically, the invention has for its object the provision of improved bearings for the rotary element of pumps of the character indicated, such bearings being self-lubricating and devoid of hydrocarbon lubricants and the like which may react with the liquid being pumped.

Another object is to provide an improved arrangement of the rotor element whereby it is relatively distant from the point where power is applied and hence little heat is conducted to the working parts.

Still another object is to provide a bearing construction in rotary pumps of the character indicated which employs at least one bearing completely enclosed from the outer atmosphere and which is self-lubricating and inert to the liquid being pumped.

Another object is to provide a pump of the character indicated with an arrangement utilizing bonded graphite as the bearing material.

Other objects of the invention will in part be obvious and will in part appear hereinafter.

The invention accordingly comprises the features of construction, combination of elements, and arrangement of parts, which will be exemplified in the construction hereinafter set forth, and the scope of the invention will be indicated in the claims.

For a fuller understanding of the nature and objects of the invention reference should be had to the following detailed description taken in connection with the accompanying drawings, in which:

Fig. 1 is an elevational view showing a pump of the turbine type arranged in accordance with the invention;

Fig. 2 is an end elevation of the pump shown in Fig. 1;

Fig. 3 is an enlarged vertical sectional view showing the pump depicted in Fig. 1, the plane of section passing through the axis of the pump;

Fig. 4 is a side elevational view of the rotor or impeller element employed in the pump shown in Figs. 1 to 3; and

Fig. 5 is a top plan view of the rotor shown in Fig. 4.

Referring now to the drawings, and particularly to Fig. 1, the pump is indicated as having a base 10 on which is mounted a casing 11 having an extension 12 in which rotates a shaft 13. The

shaft is shown as protruding from the end of the extension 12 and journaled at 14 in a manner more fully explained below.

The end of the extension 12 through which the shaft 13 protrudes is provided with a suitable shaft seal or gland. That shown in the drawings by way of example is depicted as comprising a packing 15 interposed between follower sleeves 16 and 17. The inner sleeve 16 is shown as pinned in place in extension 12, while the outer sleeve 17 is removable and pressed into place by means of a nut or cap 18 which makes screw-threaded engagement with the outer end of the extension 12. A strut 19 is also preferably interposed between extension 12 and base 10 for the purpose of insuring a more rigid alignment of the shaft with the journal at 14.

The journal mounting here provided at 14 is disposed on the base 10 in a manner independent of the pump casing in order thereby to be in poor heat conducting relation therewith. To this end, it is shown as mounted on a block 20 which is secured on base 10. Block 20 in turn supports a housing 21, the height of which may be adjusted by the insertion of shims in order to obtain the desired alignment with shaft 13. The bearing element for shaft 13, which is preferably one of the so-called "antifriction" variety, is depicted at 22 mounted in the housing 21.

30 Details of the casing 11 are shown in Fig. 3. Here, it is seen to consist of interfitting members 110 and 111. When in assembled relation, these members provide a substantially annular channel 112 which is arranged to enclose the outer or working margin of an impeller or rotor element 113 which is carried by and secured to the shaft 13. The channel 112 serves hence as the pumping channel and is formed to clear the working parts of the impeller 113 by proper clearances, that for the margin being relatively large in order that the liquid impelled may advance therethrough in a plurality of helical paths. The channel 112 is seen to have a nearly rectangular cross-section and is hence restricted at the base of the channel to provide relatively narrow clearances at the sides of the impeller. The pumping channel thus provided is circumferentially disposed about the edge of the impeller and has its inlet end in communication with a liquid inlet channel shown in Fig. 2 at 116. A similar outlet channel is provided for the other end of the pumping channel, as shown at 117.

An opening for inspection purposes is also preferably provided in the casing 11, extending from some point in the channel 112 to the exterior. Such opening is shown in Figs. 1 and 2 as being normally closed by a plug designated 119. The extension 12 is secured to the casing member 110 in any suitable manner, for example, by means of the flange 120 which is welded or otherwise

permanently secured to the extension 12, the flange being detachably secured to the casing by suitable means, for example, by bolts 121.

Details of the impeller 113 are shown in Figs. 4 and 5, where it is seen that the working margin of the impeller comprises a plurality of straight-bladed teeth 115 which are readily formed by milling machines and the like, cutting grooves, as shown at 114, which taper from the base of the working margin of the impeller, such taper providing a narrow central edge 116 which separates the liquid being pumped into the two streams forming the helices, above referred to. The central or hub portion of the impeller is shown at 123 keyed to the shaft 13 and has thrust collars 124 and 125 disposed at the sides. One or more openings 126 are also preferably provided in order to equalize the pressures on the two sides of the impellers in the central chamber of the casing in which the hub runs.

In order conveniently to position the impeller and its thrust collars on the shaft 13, one end of the same is advantageously enlarged as shown at 130. Such enlargement provides a shoulder against which the thrust collar 125 is seated. The collar 124 works against a bearing 134 held in the cupped-out portion of a disk 133 that has an inner reduced portion or nipple in screw-threaded engagement with a correspondingly threaded central recess in the casing member 110. A bearing bushing 135 is also provided for the enlargement 130. The bearing bushing may have any convenient shape, for example, cylindrical, or provided with a shoulder as shown; such bushing is advantageously supported in a removable sleeve 136 which has a closing plate 137 over the outer end secured in place in any suitable manner, for example, by bolts 138. By this arrangement shims may be introduced between the thrust collars and the impeller hub in order to achieve precise centering of the impeller in the casing.

The bearing member 135, by reason of its proximity to the impeller 113, is seen to sustain the major portion of the load. The bearing 22, in consequence, carries a relatively small portion of the load. To achieve better distribution of this major portion of the load, the shaft end 130 has been enlarged and the bearing member 135, which is thus the main bearing, is correspondingly enlarged. This bearing, by the arrangement employed, is not only totally enclosed but the inner end serves also as a thrust bearing.

In the present invention, both bearing members 134 and 135 serve without the application of any lubricant from the outside. While these members may have substantially any convenient shape, they are made of a solid self-lubricating material which is also inert to the liquid being pumped. A bonded graphite is a suitable material of this character where liquid oxygen is being pumped, and is at present preferred. Such material is not only inert to liquid oxygen and self-lubricating, but, in addition, has ability to withstand the impression of reasonable loads with a satisfactory margin of safety.

The self-lubricating bearing here employed in accordance with the invention is seen to be necessarily located inside the pump casing in order to achieve proper operating conditions. This is readily seen if it be assumed that instead of using an internal bearing, two external bearings of the type shown at 22 be employed, as is frequently done in this class of apparatus. In such an ar-

rangement the shaft would be extended through both sides of the casing, and will be twice as long as the shaft here proposed, in order to avoid the conduction of heat to the impeller. Such construction involves the use of two packings and two extension tubes. For loads of moderately high values, forces are applied to the shaft in a radial direction as a result of the reaction of the liquid on the impeller, which result in excessive deflection of the shaft at the center. This resulting deflection would cause a shifting of the impeller's position in the channel, with consequent loss of pumping efficiency or hydraulic performance. By avoiding the use of excessively long shafts, by the use of an internal bearing as here proposed, substantially all deflection of the shaft is avoided with consequent maintenance of the position of the impeller, which makes possible the employment of smaller clearances in the pump. Where the volatile liquid being pumped has a boiling point temperature at atmospheric pressure materially below 273° K. and is chemically active, such as liquid oxygen, the bearing is not only disposed within the pump casing but constructed in a manner avoiding the use of lubricants that otherwise could be applied from the outside. Hence only self-lubricating bearings, as here proposed, may be used. The relatively low temperatures at which the apparatus of the present invention is to operate is seen also to cause excessive contraction and expansion of the parts, so that even if it were otherwise feasible to use two external bearings, the resulting contraction of the parts would cause such displacement that internal rubbing between the casing and the impeller would result. By the arrangement of the present invention, such disadvantages are avoided.

While the embodiment of the invention above disclosed has been described as of the turbine type and employs but a single impeller wheel, namely, that shown at 113, it will be readily understood that the present invention is not confined to turbine type pumps but is applicable to rotary pumping apparatus in general, i. e., to centrifugal pumps, turbine pumps, gear pumps, etc. The invention is also applicable to multi-stage pumps, i. e., to pumps in which the liquid pumping element comprises a plurality of wheels arranged to pump the liquid in stages, each stage imparting a desired portion of the ultimate delivery pressure. In such pumps, the pumping channels for the several stages are of course arranged to discharge successively each into the next, i. e., in series. Such series connected channels may be collectively referred to as the "pumping channel." In any such embodiment, the invention employs a solid type self-lubricating bearing element as a main or shaft bearing, the introduction of thrust bearings being also contemplated at points where there is axial thrust to be transmitted to the reacting abutments of the casing. The embodiment of the invention illustrated in Figs. 1 to 3 is accordingly to be considered as merely exemplary and in no way excluding the application of the invention from rotary apparatus of types other than that here illustrated.

In operation, the pump of the present invention is driven by the coupling of shaft 13 to a suitable source of mechanical power, such as an electric motor. The pump is started by starting the motor and opening priming connections, the showing of which is here omitted in the interests of clearness of illustration in the draw-

ing; such however, are shown in my copending application, Serial No. 345,308, filed July 13, 1940. The shaft 13, which carries the impeller 113, is seen to run, when the pump is in operation, in an internal bearing and to be centered by thrust bearings which avoid undue friction and are self-lubricating and dispense entirely with the use of any liquid hydrocarbon lubricants. The use of a remote bearing at 14 for the protruding end of shaft 13 operates to reduce substantially to a minimum the conduction of heat to the pump casing which might otherwise interfere with the pumping efficiency of the pump.

While the present invention has been described in connection with rotary type pumping apparatus, the invention is not necessarily confined to any such apparatus, the invention being obviously applicable to apparatus wherever there are moving parts that are subject to relatively low temperatures, such as those materially below 273° K., and where the normal expansion and contraction of the parts would result in such movement or displacement of the parts as to interfere with the normal operating conditions when the apparatus has been cooled to the relatively low operating temperatures here contemplated.

The pump of the present invention is particularly adapted for use as a fore pump or first-stage pump in the apparatus disclosed in the U. S. patent to Thompson, No. 1,930,731, the general role and operation of the present type of pump being disclosed in my copending application, Serial No. 340,848, filed June 15, 1940, issuing August 11, 1942 as Patent No. 2,292,375. Other features of construction disclosed herein but not claimed are set forth in my copending application, Serial No. 345,308, filed July 13, 1940.

Since certain changes may be made in the above construction and different embodiments of the invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In rotary type pumps and the like adapted for pumping a volatile liquid having a boiling point temperature at atmospheric pressure materially below 273° K., the combination with a casing having a liquid inlet, a liquid outlet and a circumferentially disposed pumping channel therebetween, of a shaft rotatively disposed in said casing having an enlarged end and provided with a rotary pumping element adjacent said end and cooperatively disposed with respect to said pumping channel, means on said shaft in said casing including self-lubricating thrust bearings engaged between each rotor side and the casing portion adjacent thereto for positioning said rotor relatively to the casing and maintaining an equal thrust on each side of said rotor, and a bearing sleeve of self-lubricating material in said casing for said enlarged shaft end, said self-lubricating material comprising bonded graphite and said sleeve cooperating with the thrust bearing adjacent thereto.

2. A rotary type pump adapted for pumping a volatile liquid having a boiling point temperature at atmospheric pressure materially below 273° K., having in combination a casing, a liquid

inlet and a liquid outlet therefor, a circumferential pumping channel extending from said inlet to said outlet around a major portion of the circumference, a shaft rotatably disposed in said casing, a rotary pumping element mounted thereon adapted to operate in said channel and having a relatively small clearance between it and the casing in the region thereof between its hub and said pumping channel, said shaft having an inner end terminating in said casing with said pumping element secured at its hub for rotation by the shaft and positioned on the shaft closely adjacent said end, a bearing in said casing for supporting said inner shaft end, said end and bearing being totally enclosed within the casing, and thrust-bearing means in said casing including self-lubricating thrust bearings about said shaft engaged between each pumping element hub side and the casing portion adjacent thereto for positioning said pumping element relatively to said casing to maintain said clearance substantially constant.

3. In rotary type pumps and the like adapted for pumping a volatile liquid having a boiling point temperature at atmospheric pressure materially below 273° K., the combination of a casing, a liquid inlet and a liquid outlet therefor, a circumferentially disposed pumping channel extending from said inlet to said outlet, a shaft rotatably disposed in said casing, a rotary pumping element mounted thereon adapted to operate in said channel and having a relatively small clearance between it and the casing in the region thereof between its hub and said pumping channel, said shaft having an inner end terminating in said casing with said pumping element secured to the shaft closely adjacent said end, a bearing sleeve of solid permanently self-lubricating material in said casing for supporting said inner shaft end, said shaft end and bearing sleeve being totally enclosed within the casing, means about said shaft in said casing including self-lubricating thrust bearings engaged between each pumping element hub side and the casing portion adjacent thereto for positioning said pumping element relatively to said casing to maintain said clearance substantially constant, and a tubular member extending from said casing toward the other end of said shaft and having a shaft seal, and an outer bearing for said shaft beyond said tubular member remote from and independent of the main pump casing.

4. In rotary type pumps and the like, for pumping a volatile liquid having a boiling point at atmospheric pressure materially below 273° K., the combination with a casing having a liquid inlet, a liquid outlet, and a circumferentially disposed channel, of a shaft rotatively disposed in said casing and provided with a rotary pumping element or rotor cooperatively disposed with respect to said inlet, said outlet, and said pumping channel, said casing having portions on each side of said rotor axially spaced from said rotor, and means about said shaft in said casing including self-lubricating thrust bearings engaged between each rotor side and the said casing portion adjacent thereto for positioning said rotor relatively to said casing and maintaining a substantially equal thrust on each side of said rotor irrespective of the effects of temperature changes.

ODD A. HANSEN.
